UNITED STATES PATENT OFFICE.

JOSEPH W. DOUGLAS, OF MIDDLETON, CONNECTICUT, ASSIGNOR TO W.
& B. DOUGLAS, OF SAME PLACE.

IMPROVEMENT IN PUMPS.

Specification forming part of Letters Patent No. 144,965, dated November 25, 1873; application filed September 2, 1873.

To all whom it may concern:

Be it known that I, JOSEPH W. DOUGLAS, of Middletown, in the county of Middlesex and State of Connecticut, have invented an Improvement in Pumps, of which the following is a specification:

Figures 1 and 2 are side views of my improved pump. Figs. 3 and 4 are sectional side views, showing modifications of the style of braces used; and Fig. 5 is a side view of the clamp for holding the brace in position.

Similar letters of reference indicate corresponding parts in the several figures.

This invention has for its object to dispense with the heavy and cumbersome standards usually employed on ordinary pumps for holding the same in position on the ground, on elevated stands, or in sinks, which standards require the use of various patterns and core-boxes, &c., for casting them, and cause the pumps to be more expensive and cumbersome than they would be without requiring such standards.

My invention consists in combining, with the pipe of an ordinary pump, an adjustable sleeve or clamp, to which one or more braces are fixed, and which can be fastened to the said pipe by means of cross-clamps, or otherwise, so that the pump may, by the braces, be steadied and properly supported. These braces may be made extensible or in single pieces, as desired.

In Fig. 1 in the accompanying drawing, the letter A represents the chamber of an ordinary pump, carrying a spout, a, and a support for the handle B. C is the pipe of the pump, extending downward from the chamber into a well, or toward the water-receptacle. Upon and around this pipe C is fitted a sleeve, D, which can be fastened to the pipe at any suitable height by means of a set-screw, e, or by a wedge, or other suitable clamping or fastening devices. The sleeve constitutes a base or flange on the pipe, for supporting the same and the superstructure on a frame, platform, or sink, E. By making it adjustable on the pipe, in the manner indicated, the pump can be set at suitable height. Around the pipe C, and above the sleeve D, is also fitted another sleeve, F, which can also be adjusted vertically, and fastened by a set-screw, d, or its equivalent. The brace G is pivoted to projecting ears of the sleeve F, and extends down to the supporting platform or plate E,

serving, in conjunction with the sleeve D, to properly hold the pump in position, and to steady the same during operation.

It will be observed that, by thus making the supporting parts of the pump in the form of adjustable sleeves, or as parts thereof, the upper portion of the pump can be made much lighter than is usually the case where the pump support has to be cast together with the chamber A, and a smaller chamber is, therefore, permissible in the pump.

In Fig. 1, the operating-chamber of the pump is shown to be suspended from the pipe C beneath the platform E, so that C is, in this case, not the suction, but the intermediate, pipe.

Fig. 2 represents a drive-well pump, provided also with a chamber, A, that is supported on the pipe C. On this pipe is an adjustable sleeve, F, to which a series of standards, G, are connected. When there are two or more such standards G, the sleeve D may be dispensed with, as shown in Fig. 2.

Instead of making the sleeve F in one single piece and slipping it over the end of the pipe C, I may make it in section and apply it around the pipe C at any desired position, and then clamp it by means of clamping-rings e, or otherwise.

The standards may be in single pieces, as shown in Figs. 1 and 2, or they may be made extensible and contractible, as shown in Fig. 3, and provided with pivoted feet at their lower ends, as shown in the same figure.

Fig. 4 represents an enlarged side view of the pipe C, and of the appliances shown in Fig. 1. It will be fully understood without further description.

Fig. 5 shows a sleeve, F, when made in pieces, and applied around the pipe C by means of split rings or clamps e.

I prefer to use the set-screw d, or its equivalent, on such split or sectional sleeve F, the same as I use on the single sleeve F.

I claim as my invention—

The combination of the sleeve F, carrying the brace or standard G, with the pipe C of a pump, as specified.

In testimony whereof I have hereunto signed my name before two subscribing witnesses this 8th day of July, 1873.

Witnesses: JOS. W. DOUGLAS.
